UNITED STATES PATENT OFFICE.

T. DERINGTON, OF CARBONDALE, ILLINOIS.

IMPROVEMENT IN MACHINES FOR TURNING WAGON-SPOKES.

Specification forming part of Letters Patent No. 57,099, dated August 14, 1866.

To all whom it may concern:

Be it known that I, T. DERINGTON, of Carbondale, Jackson county, State of Illinois, have invented certain new and useful Improvements in Machinery for Turning Spokes; and I do hereby declare that the following is a full, clear, and exact description thereof, reference being had to the accompanying drawings, making a part of this specification, in which—

Figure 1 is a front elevation of the improved machine for turning wagon-spokes. Fig. 2 is a transverse section through the machine, taken in the vertical plane indicated by red line $x\ x$ in Fig. 1. Fig. 3, Sheet 2, is a top view of the machine. Fig. 4, Sheet 2, is a transverse section taken in the vertical plane indicated by red line $y\ y$ in Fig. 1.

Similar letters of reference indicate corresponding parts in the several figures.

This invention relates to certain novel improvements in the spoke-turning machine which was secured to me by Letters Patent bearing date January 26, 1864, in which a vibrating cutter-carriage was operated by means of a spirally-grooved pattern in such manner that, by the revolution of such pattern, the cutters were guided and their movements controlled by said pattern.

One of the objects of my invention is to so construct a spirally-grooved feeding and shaping pattern for controlling the action of the cutters that this pattern shall give a fast feeding-motion to the carriage which supports the cutters during the operation of cutting that portion of the spoke which is nearly cylindric, and a slow feeding-motion thereto during the operation of cutting that portion of the spoke which is nearly flat and very irregular, thus adapting the speed of the cutter-carriage to the varying irregularity of the spokes, and producing thereby smoother spokes, or causing the cutters to perform smoother work on the sloping or wide and nearly flat portion of the irregular articles being turned.

Another object of my invention is to suspend the cutter-carriage by means of grooved rollers upon a rail in such manner that the carriage is free to vibrate and to conform to the irregular shape of the pattern, and also to move steadily back or forward in a direction with the length of this pattern, and to support said

guiding-rail upon a beam which is susceptible of being adjusted parallel toward and from the work or front part of the machine, as will be hereinafter described.

Another object of my invention is to provide for holding the cutter-frame up to the pattern by a spring, and to rotate the cutter-shaft on said frame by means of traveling belts acting on each end of this shaft, so as to preserve a uniform bearing on each side of the cutter, as will be hereinafter described.

Another object of my invention is to provide an auxiliary set of cutters on the right and left side of a main set of cutters, which sets of auxiliary cutters do not extend out as far as the said main cutters, and by this means, in connection with the reciprocating movement of the carriage which supports the cutters, and a consequent back and forward feed of the cutters, prevent a splintering or slivering of the wood both during the cutting of a spoke in the forward and backward movements of the carriage. My construction of the cutter is such that only one set of auxiliary cutters acts at a time, this operation being so whether the spoke is cut at its large or small end first, for the reason that the main set of cutters projects out far enough beyond the auxiliary sets of cutters to leave a clear track for that set of auxiliary cutters which follows after it; and thus, when the right set of auxiliary cutters has, by preceding the main or finishing set, cut the rough wood away, and the main set has followed them and cut into the wood still deeper, there is nothing which remains to be done by the left auxiliary set. But when another blank for a spoke is substituted for the finished spoke and the motion of the cutter-carriage reversed, the left set, by becoming the preceding cutters to the main or finishing cutters, the work of roughing the stuff devolves upon said left set of cutters, and nothing is left to be done by the right auxiliary set of cutters, and this is so although the spoke is cut from its broad end toward its small end, because the main cutters cut deep enough to remove all wood out of the path of the cutters which follow them.

To enable others skilled in the art to understand my invention, I will describe its construction and operation.

In the accompanying drawings, A repre-

sents the frame of the machine, which is constructed with its front side and ends vertical and its rear side inclined, as shown in the drawings, for the purpose of affording a wide base and steadiness. Near the base of this frame is a horizontal drum, B, which should be arranged so that it will be parallel to the axis of the pattern that controls the movements of the cutter-frame. The length of this drum B should be somewhat greater than the distance required for the cutter-carriage to travel, so that the belts B' B', which pass around this drum and also around pulleys *a* *a* on the cutter-shaft *a'*, shall have freedom to travel the required distance.

The cutter-shaft *a'* has its bearings in a vibrating pendant or frame, C, and is driven by means of the two belts B' B', passing over the two pulleys on the extremities of said shaft. By thus having two driving belts and pulleys the cutter-shaft will have an equal bearing on each side of the cutter-head C', and will run with much less friction and vibration than if only one driving-belt was used. The cutter-carriage will also be held in a much steadier position by this arrangement.

The carriage C is suspended from a longitudinal beam, C², by means of two straps, *b*, which are placed astride of this beam and provided with grooved roller-supports *b' b'*, which are guided and kept in place by means of a rail, *b²*, upon which said rollers move. This rail *b²* and the supporting-rollers *b' b'* allow the lower end of the carriage C to swing freely up to and from the pattern, as will be herein-after described. They also allow said carriage to be moved freely by the pattern backward or forward in a direction with the length thereof.

Near the lower end, and in front of the carriage C, a stud, *c*, is secured rigidly to it, which stud has a tooth, *c'*, applied to it so as to fit loosely in a spiral groove, *e*, which is formed in the surface of a pattern, D, as shown in Figs. 1 and 4. This pattern D is confined between two centers, *i i'*, projecting from the main frame A, so that its axis of motion is parallel to the beam C² and driving-drum B. The center point, *i'*, is the inner termination of the shaft of a wheel, E, which receives a rotary motion from the main drum B through the medium of belts and pulleys, as will be herein-after described. As the pattern D is thus rotated the spiral groove *e* will move the carriage C upon its rail, and thus produce the feed for the cutters. The tooth *c'* is kept in the groove *e* of the pattern D by means of a curved spring, *e'*, (shown in Fig. 4,) which is affixed to the lower end of the carriage C at one end and hooked over a longitudinal rod, *f*, at the other end. To allow this latter end of the spring *e'* to move freely over its rod *f*, I apply an anti-friction roller, *f'*, to it, as shown in Fig. 4. The spring *e'* will keep the tooth *c'* in its groove, and at the same time allow the lower end of the cutter-carriage to vibrate and conform to the irregular shape of the pattern.

The spur-wheel E engages with a spur-wheel, E', of a corresponding size, on a shaft, *g*, which shaft has a centering chuck or pin, *g'*, on its inner end, for receiving and centering one end of the stuff of which a spoke is formed. The opposite end of the stuff is centered by an adjustable pin, *g²*, whose axis coincides with the axis of the shaft *g*. The axis of the shaft *g* is parallel to the axis of the shaft of the wheel E.

The wheel E' engages with a pinion spur-wheel, *h*, which is keyed on a short shaft, *h'*, and this shaft carries two fast pulleys, *j j*, and two loose pulleys, *k k*, over which pass belts *h² h³*, that receive their motion from the pulleys F. The belt *h²* is crossed, but the belt *h³* is not. Consequently, by shifting these belts upon their respective pulleys *j k*, the motions of the wheels E E and the pattern D can be reversed as desired.

The pulleys F are rotated by means of a belt, *k'*, which passes over a pulley on one end of the shaft of the drum B, as shown in Fig. 2.

It may be desirable at times to reverse the feed-motion by hand, and at other times to do it automatically; and to this end I have arranged the belt-shifter G, as shown. This shifter consists of a rod having two toes, *l l*, fastened to it at suitable points, and also two loops, *m m*, which latter pass around the belts *h² h³*, and shift these belts when the rod G is moved end-wise.

The toes *l l* are located at such a distance apart and arranged in such relation to the length of the stuff which is being turned that when the cutter-head C' arrives at the termination of its forward stroke the carriage C will strike one of said toes and shift the belts, so that they reverse the movement of the pattern, which then moves the carriage back until the carriage strikes the other toe *l*, when the movement of the carriage will again be reversed. By moving the rod G by hand the motion of the carriage C can be reversed at any time.

The extremities of the beam C², from which the carriage C is suspended, are fitted into the transverse supporting-beams of the frame A, so as to receive a lateral adjustment without being moved out of its parallel position with relation to the pattern D. This adjustment of said beam is effected by means of two toothed segments, *n n*, which are keyed to a longitudinal rod, J, that carries a hand-crank on one end. The toothed segments *n n* engage with racks *p p*, which are secured to the beam, so that by slightly turning the rod J the beam C² can be moved forward or backward without losing its parallelism.

The rotary cutter-head C' is constructed with annular flanges on its sides, which are slotted to receive the shanks of the cutters S S'. The side cutters, S, are made in the form of hooks curving outward, as shown in Fig. 1, and are used for the purpose of reducing the rough surfaces of the stuff preparatory to smoothing it by means of the intermediate looped cutters, S'. (Shown in Fig. 3.)

The intermediate cutters, S', are to project far enough from the head C' beyond the auxiliary sets of right and left cutters S S to cut away all wood which would come in the path of whichever of the auxiliary sets that is following behind it; and the auxiliary sets of cutters are to project from the head C' far enough to enable one or the other set, accordingly as the direction of the feed of the cutter-carriage may require, to rough and prepare the wood for the following finishing or main set of cutters.

The cutters S are curved or hook-shaped for the purpose of preventing the stuff from slivering during the operation of cutting it. They precede the cutters S' and prevent these cutters from slivering the stuff. Both sets of cutters may be applied to their circular head C', so that they can be adjusted at pleasure.

The pattern D is made so that it conforms in shape to the shape of the spokes or other objects desired, after which this pattern is grooved, as shown in Fig. 1, the groove passing spirally around it and extending from one end to the other. In forming this spiral groove e in the pattern D, reference must be had to the varying diameter or thickness of the pattern, and as its diameter increases the spaces between the grooves must be diminished, so that the cutter-carriage will not be moved as fast during the operation of cutting the sloping or irregular nearly flat portions of a spoke as it is moved during the operation of cutting the nearly cylindric portions thereof.

By this mode of grooving the pattern it will be seen that as the irregularity of work increases the speed with which the carriage and its cutters are moved will be diminished.

Having thus described my invention, what I claim as new, and desire to secure by Letters Patent, is—

1. The feeding and governing pattern, constructed with irregular grooves or threads, substantially as and for the purpose set forth.
2. The arrangement of rollers b' b', straps b b, and horizontally-adjustable beam C², with rail on its top, in a machine which is constructed and operated substantially as described, all for the purpose set forth.
3. The arrangement of the spring e', with its roller f', upon the cutter-carriage, and the rail f, for holding the tooth c' up to the pattern, substantially as herein described.
4. The arrangement, with the cutter-head, of a pulley on both ends of its shaft, and applying belts, which move with the cutter-carriage, on both of said pulleys, of the head, all for the purpose of driving the cutter with a more regular and steady motion, as herein set forth.
5. The combination of a cutter-head, constructed with right and left auxiliary sets of cutters S S and a central main or finishing set of cutters, with a reciprocating carriage and the feeding-pattern, constructed as described, so that the work of roughing and smoothing is performed at one time, and also during the back as well as the forward movement of the cutter-carriage, substantially as herein described.
